UNITED STATES PATENT OFFICE.

WILLIAM J. MALCOLMSON, OF CICERO, AND HARRY BLOUNT, OF OAK PARK, ILLINOIS,
ASSIGNORS TO WESTERN ELECTRIC COMPANY, INCORPORATED, OF NEW YORK,
N. Y., A CORPORATION OF NEW YORK.

ASSEMBLING DEVICE FOR VACUUM TUBES.

1,403,800.

Specification of Letters Patent. Patented Jan. 17, 1922.

Application filed December 29, 1919. Serial No. 348,013.

To all whom it may concern:

Be it known that we, WILLIAM J. MALCOLMSON and HARRY BLOUNT, citizens of the United States, residing at Cicero, in the county of Cook and State of Illinois, and at Oak Park, in the county of Cook and State of Illinois, respectively, have invented certain new and useful Improvements in Assembling Devices for Vacuum Tubes, of which the following is a full, clear, concise, and exact description.

This invention relates to an assembling device for vacuum tubes, and more particularly it relates to a device which may be used in the manufacture of vacuum tubes for temporarily holding in their proper relationship certain parts of such a tube while they are being permanently attached.

For purposes of illustration, this invention will be described and illustrated as an assembling device which may be employed in the basing operation of that type of vacuum tube which embodies a glass bulb connected to a base comprising an outer shell and an inner block, which latter carries the terminals connected to the electrodes within the bulb. In assembling such devices, the shell and the block may be secured together and the bulb anchored therein by a filler, such as sealing-wax, which is poured onto the block and which acts as an insulating medium between the terminals.

A further object of this invention is to provide a circumferentially complete member outside the shell and adjacent one edge thereof for preventing the sealing-wax or other filler from getting on the outside of the shell during the process of assembling the shell and the block.

The preferred form of this invention comprises a socket, adapted to support the base of a tube in combination with means for supporting the bulb and pressing it endwise into the base. Means are also preferably provided for interlocking the base and the socket. Such a device is simple and durable, and is one to which the tubes may be applied or from which they may be removed with ease and rapidity.

This invention will be better understood by reference to the following detailed description and the accompanying drawings.

In the drawings:

Fig. 1 is a perspective view partly in section and partly broken away, of an assembly device constructed in accordance with and illustrating one embodiment of our invention;

Fig. 2 is a perspective view of the completed tube base; and

Fig. 3 is a detail view of the insulating block within the shell of the tube.

Similar reference numerals throughout the views indicate the same parts.

The vacuum tube of the kind worked upon is shown in Fig. 1, and referring thereto 1 indicates the tube or bulb, 2 the base shell in which it is supported, 3 the block within the shell and 4 the terminals carried by the block and connected to the electrodes (not shown) within the bulb. The block 3 is of irregular web-like form, as shown in Fig. 3, and is made of insulating material. This block is inserted in the shell 2 and is adapted to rest upon an inner ledge 3' formed in the shell. After the block is inserted the shell adjacent it is crimped as at 2' to hold the block in place. To the block are fastened the plates 4' for the wires leading from the electrodes within the glass bulb, and these plates 4' are electrically and mechanically connected to the terminals 4. The structure provided for the reception of the tube is generally of a tube-like form and comprises a hollow lower portion 5 in which are anchored a plurality of upwardly projecting bolts or posts 6.

The lower sleeved ends 7 of these posts project freely within the interior of the portion 5. One of the posts 6, which is shown to the right of tube 1 in the drawing, has its upper end threaded into a cap piece 8, on which are fitted a sleeve 9 and a collar 10 to support an upper structure consisting, in the present instance, of an intermediate annulus 11 and an upper socket member 12. As shown in the drawing, that portion of cap piece 8 between annulus 11 and the collar 10 is of considerably less diameter than other portions thereof, so that if desired, a suitable supporting arm for the fixture may be placed in engagement with this small portion of cap piece 8. The other posts 6 are threaded into cap pieces 25 which extend

upwardly and are suitably fastened to the flange of the socket member 12. The flange of the socket member 12 and the annulus 11 are spaced apart by sleeves 26 while annulus 5 11 is spaced apart from the base portion 5 by other sleeves 27. The said socket member is provided with a bayonet slot opening 13 at its upper edge and its interior diameter is such that the tube base 2 will fit 10 closely therein. Coiled about the sleeves 7 at the lower end of the bolt 6, and resting upon the heads 14 of these bolts, are arranged light springs 15 of the compression type. They bear at their upper ends against 15 the under side of a platform 16 that is guided slidably upon the sleeves 7 in a vertical direction, and is provided with a central opening 17. The openings in sleeves 11 and 12, part 5 and plate 16 are so made that when 20 the bulb and shell are in position therein, the bulb and shell are in axial alignment.

In the operation of the device, the tube, inverted, is thrust into the support until the lower end of the bulb 1 engages the platform 25 16 within the opening 17, and depresses it. At the same time the locking pin 18 projecting laterally from the side of the base of the tube enters the bayonet slot 13 in the socket 12. A subsequent rotary movement of the 30 tube interlocks the projection 18 thereof in the bayonet slot 13, confining the base in its socket and placing the springs 15 under tension so that they act to thrust the bulb 1 into the base of the tube and firmly hold it 35 there. The aperture 17 in the platform centers the bulb, permits its rotation and protects the usual tip 19 formed at its end. A ring 20 having an inner shoulder 21, which rests on the upper edge of socket member 40 12, and an upper beveled surface 22, is adapted to be slipped in place after the tube is placed in this device and closely embraces the end portion of the shell 2 of the tube. The upper portions of the beveled face 22 45 and the edge of the shell lie closely together so that when the sealing wax is poured into the shell any of it running over will run down the bevel portion 22 instead of down between the ring 20 and the shell 2.

50 The sealing wax in a fluid state, can now be poured into the base shell of the tube to cover the block 3, and, when cooled, forms a solid body occupying the space between the block and the rim of the shell, as indicated at 23 in Fig. 2. It flows into the crevices between the parts and when hardened it holds the bulb, shell and block firmly together. The tube is removed by a downward and then a rotary movement that 55 60 disengages the interlock at 18, and the apparatus is in readiness to receive the next article. There is a considerable space between the upper face of portion 5 and the annulus 11 through which the evacuated vessel 1 may 65 be seen. Through this space the glass bulb

may be manually manipulated (to adjust the plane of the electrodes) into proper relation to the shell while the sealing wax is hardening. The sighting pin 28 may be employed, if desired, to insure that the electrodes in the 70 tube are in the desired relation with respect to the bayonet pin 18 of the base.

The device when constructed in the manner shown amply protects the fragile tube and also serves to dissipate the heat ab- 75 sorbed from the molten wax.

What is claimed is—

1. In an assembling device for vacuum tubes comprising a bulb and a base, the combination of a substantially cylindrical 80 socket open at both ends and adapted to support said base, and yielding means acting in a direction towards the socket adapted to support said bulb and to press it endwise into said base, the end of said socket opposite said bulb being adapted to receive a sealing medium.

2. In an assembling device for vacuum tubes comprising a bulb and a base, the combination with a socket adapted to support 90 the base, of yielding means acting in a direction toward the socket adapted to rotatably support the bulb and press it endwise into the base, and a locking device in the socket adapted to operatively engage the base 95 through a rotary movement of the latter.

3. In an assembling device for vacuum tubes comprising a bulb and a base, the combination with a socket adapted to support the base in an inverted position and a tubular support for the socket, of means on the latter adapted to interlock with the base, and a yielding platform within the support adapted to engage the bulb and thrust it into the base, said support being adapted at 100 105 its end opposite said bulb to receive a sealing medium.

4. In an assembling device for vacuum tubes comprising a bulb and a base, the combination with a socket adapted to support 110 the base in an inverted position and a tubular support for the socket composed of a plurality of annular members connected together by longitudinally extending posts, of means on the socket adapted to interlock 115 with the base, a platform guided on the posts below the socket and adapted to engage the end of the bulb, and coil springs surrounding the posts beneath the platform to press the bulb into the base.

5. In an assembling device for vacuum tubes comprising a bulb and a base, the combination with a socket adapted to support the base in an inverted position and having a bayonet slot therein adapted to interlock with a lateral projection on the base by 120 a rotary movement of the latter and a tubular support for the socket composed of a plurality of annular members connected together by longitudinally extending posts, a 125 130

- platform guided on the posts below the socket and having a central opening adapted to be rotatably engaged by the end of the bulb, and coil springs surrounding the posts beneath the platform to press the bulb into the base.
6. In an assembling device for a vacuum tube comprising a bulb and a base, a support for said bulb, and means comprising a tubular member of substantially uniform diameter throughout its length and open at both ends for holding said base in axial alinement therewith while said parts are being secured together.
- 10 7. In an assembling device for a vacuum tube having two cylindrical parts, a support for one of said parts, and means comprising a tubular member of substantially uniform diameter throughout its length and open at both ends for holding the other of said parts in axial alinement therewith while said parts are being secured together.
- 15 8. In an assembling device for vacuum tubes, a ring adapted to engage the shell of a tube base, said ring having a beveled edge, and means for maintaining said beveled edge adjacent one edge of said shell.
- 20 9. In an assembling device for vacuum tubes comprising a bulb and a base, the combination of a socket adapted to support said base, a platform adapted to engage the end of said bulb, and a plurality of spaced resilient means for causing said platform to press said bulb into said base.
- 25 30 10. In an assembling device for vacuum tubes comprising a bulb and a base, the combination of a socket adapted to support said base, yielding means acting in a direction to- wards said socket for supporting the bulb and for pressing the bulb endwise into said base, a pin on said base, and a bayonet slot in said socket cooperating with said pin for interlocking said base and said socket.
- 35 11. In an assembling device for vacuum tubes comprising a bulb and a base, the combination of a socket for supporting said base, a plurality of spaced discs surrounding said bulb for holding said bulb in axial alignment with said base, and resilient means for pressing said bulb into said base.
- 40 12. In an assembling device for vacuum tubes comprising a bulb and a base, the combination of a socket for supporting said base, a support for said bulb, and a ring mounted on said socket and having a beveled edge adjacent one edge of said base.
- 45 13. In an assembling device for vacuum tubes comprising a bulb and a base, the combination of a socket for supporting said base, resilient means for pressing said bulb into said base, and a plurality of standards disposed around said bulb for connecting said means and said socket.
- 50 14. In an assembling device for vacuum tubes comprising a bulb and a base, the combination of a socket for supporting said base, resilient means for pressing said bulb into said base, said socket having a flange, and posts arising from said flange for supporting said resilient means.
- 55 60 70 15. In witness whereof, we hereunto subscribe our names this 19th day of December A. D. 1919.
- WILLIAM J. MALCOLMSON.
HARRY BLOUNT.
